His Attorney.

UNITED STATES PATENT OFFICE.

JOHANNES BRUYNES, OF EINDHOVEN, NETHERLANDS, ASSIGNOR TO GENERAL ELECTRIC COMPANY, A CORPORATION OF NEW YORK.

SWITCHING DEVICE.

Application filed May 12, 1924, Serial No. 712,721, and in the Netherlands May 28, 1923.

My invention relates to switching devices. More in particular it relates to a switching device adapted for use, for example, with a device having a positive resistance characteristic such as a tungsten lamp. Furthermore, with my invention a bimetallic interrupter may be effectively used with an electric lamp circuit to interrupt said circuit at regular intervals.

10 The invention is based on the observation that the high current which flows when the circuit is initially closed through a tungsten lamp has a detrimental effect. By reason of the momentary rush of high current 15 when the circuit is initially closed (which is several times the value of the current after the lamp comes into full operation), the contacts of the interrupter become welded together.

20 According to the invention, means are provided such that the total resistance in the circuit of the interrupter and the lamp varies in such a manner after the circuit is closed that the current when the circuit is 25 initially closed is not materially higher than the current shortly thereafter, that is, than the normal operating current.

It will be understood that by the expression "not materially higher" is meant not 30 sufficiently higher to bring about the welding of the contacts. In the preferred arrangement the initial current flow and the normal operating current are made as near equal as possible. It is also possible to so 35 arrange the elements that the initial current may be less than the normal operating current. However, good results are obtained when the initial current has a value of, for example, three times that of the operating 40 current.

When a lamp with a tungsten filament is used a resistance may be connected, for example, in series with the lamp and the interrupter, which, after the lamp has been 45 switched on, remains unvaried or decreases so that the increase of resistance of the filament is partly compensated for and becomes of less influence.

According to the invention, a resistance 50 may also be connected in parallel with the interrupter, such that during the period that the contacts are open a current flow is maintained through the filament but of such

small magnitude that the filament barely glows or does not glow at all. The temperature of the filament nevertheless is maintained at such a degree that the current at the moment of closure of the contact is not materially higher than the operating current. With this arrangement, the filament 55 may be mounted in one lamp with the resistance connected in parallel to the interrupter.

According to the invention, the interrupter is preferably connected in series with 60 a carbon filament lamp. As the resistance of the carbon filament decreases as the temperature increases the object of the invention is thus attained in a very simple and entirely satisfactory manner. A very practical embodiment of the invention is obtained by mounting an interrupter in the 65 cap of a carbon filament lamp and connecting it in series therewith.

It is essential on the one hand that the 70 contacts of the interrupter should not adhere together and on the other hand it is desirable to provide for easily regulating the lengths of the period during which the circuit is 75 open and during which the circuit is closed.

According to the invention, this is possible 80 by disposing the contact opposite the bimetallic strip on a resilient member, and by determining the extreme position of said member adjacent the bimetallic strip by 85 means of an adjustable hook or similar member.

The accompanying drawing represents an 90 example of an interrupter and a device according to the invention with an interrupter.

Referring more in detail to the drawing, Fig. 1 indicates a construction of an interrupter according to the invention. The contacts of the interrupter are represented as 95 being enclosed within an exhausted envelope or within an envelope filled with a neutral gas. It is, of course, obvious that the invention is not limited to the use of contacts thus enclosed. In fact, the contacts may be used in the open air.

Fig. 2 represents diagrammatically a device according to the invention which comprises an interrupter and a resistance connected in parallel with the interrupter.

The interrupter shown in the drawing, Fig. 1, comprises a glass vessel 1 with a

stem 2 in which the leading-in wires are sealed. The glass vessel may be partly or wholly exhausted or it may be filled with a neutral gas such, for example, as nitrogen or 5 argon at a suitable pressure.

The conductor 3 serves for feeding the current to the heating wire 5 which is wound on a bimetallic strip 6 but insulated therefrom in some suitable manner, as for example by mica plates. The wire 5 ends in contact 9. The conductor 4 feeds current to a support 8. The support 8 itself is preferably non-resilient and by bending the hook 11 more or less the contact 10 may be easily 10 adjusted. It is thus possible to regulate the period of switching on and disconnecting the lamp.

The bimetallic strip on growing hot bends upwards until the contact 10 has reached its 20 extreme position, whereupon the current is interrupted. The strip 6 first bends slightly further but cools and returns, the contact with the spring 7 being thus restored so that the current flows again.

25 The interrupter may be mounted in any suitable manner in a lamp socket. The tungsten lamp with the current limiting resistance, or a carbon filament lamp alone, may be connected in series with the interrupter. 30 It is also possible to mount the interrupter in the lamp cap.

The device shown in Fig. 2 has a filament 15 consisting for example of tungsten and connected in series with an interrupter provided with a bimetallic strip 18, which has a contact 19 that periodically contacts with a spring 17.

40 The filament and the interrupter are connected to a network of some suitable alternating or direct voltage V. A resistance 16 is connected in parallel to the interrupter.

The operation of the device is as follows: During the heating period of the interrupter, the resistance 16 is shortcircuited and 45 the full current flows through the filament 15 which consequently becomes incandescent. By reason of the bimetallic strip growing hot the circuit is interrupted, the resistance 16 and the filament 15 being thus connected 50 in series to the voltage V. The current is

then lower than the operation current and has such a value that although the filament 15 gives out light no longer, it yet remains at a rather high temperature, so that when the interrupter closes the circuit again, the 55 switching-on current is not materially higher than the operating current.

It is, of course, obvious that the relation between the initial current and the operating current can be fixed by regulating the 60 value of the resistance 16, as the said value determines the temperature of the filament at the end of the opening period.

Good results can be obtained if the value of the resistance 16 is, for example, equal to 65 three times that of the resistance of the filament 15 in a cold state.

The resistance 16 may have the form, for example, of a tungsten filament and in that case the filament and the resistance may be 70 mounted together in one lamp.

It will be understood that I do not wish to be limited to the specific construction of my invention shown and described inasmuch as variations thereof will readily suggest 75 themselves to those skilled in the art without departing from the spirit of my invention or from the scope of the claim herein.

What I claim as new and desire to secure by Letters Patent of the United States is:— 80

In an electric device, the combination of a lamp filament having a positive temperature-resistance characteristic, a resistance element with a negative temperature-resistance characteristic, a thermostatic switch 85 having contacts for periodically short-circuiting the resistance element, an electric heater for the thermostat connected in series with one of said elements whereby when the device is connected to a source of current the 90 filament may be made to flash on and off, said elements being connected in series with respect to the current source whereby a harmful surge of current through said contacts during the operation of the thermostat is 95 prevented.

In witness whereof, I have hereunto set my hand this twenty-second day of April, 1924.

JOHANNES BRUYNES.
